TOOL

Isidore Finkel, Brooklyn, N. Y.

Application June 18, 1936, Serial No. 85,835

15 Claims. (Cl. 29—33)

This invention relates generally to tools. More particularly, it relates to the type of tools which are adapted for use in connection with the assembling and disassembling of cable fittings and cables.

One of the objects of this invention is to provide a tool of the character described having means for quickly removing a cable fitting from a cable, without injuring the fitting so that it 10 may be again used in connection with another cable.

Another object of this invention is to provide in a tool of the character described, means for non-destructively removing a fitting from a cable 15 in association with means for assembling a cable and fitting.

A further object of this invention is to provide a tool of the character described which is rugged in construction, relatively inexpensive to manufacture, which shall comprise few and simple parts, which shall be easy to assemble and to 20 operate, and yet possess a high degree of efficiency.

Other objects of this invention will in part be 25 obvious and in part hereinafter pointed out.

The invention accordingly consists in the features of construction, combinations of elements, and arrangement of parts which will be exemplified in the construction hereinafter described, 30 and of which the scope of application will be indicated in the following claims.

In the accompanying drawing, in which is shown one of the various possible embodiments of this invention,

Fig. 1 is a side elevation, partly sectional, of an assembled device embodying my invention;

Fig. 2 is a plan view of the device illustrated in Fig. 1;

Fig. 3 is an enlarged detail sectional view taken 40 substantially on the line 3—3 of Fig. 1;

Fig. 4 is a view taken substantially on the line 4—4 of Fig. 1 illustrating a portion of the device embodying my invention;

Fig. 5 is a view taken substantially on the line 45 5—5 of Fig. 1 illustrating still another portion of the device embodying my invention; and

Fig. 6 is an elevational view illustrating a cable and fittings in assembled relationship.

It has been found that cables of the type generally employed in flexible drive shafts for automobile, radio and for other similar uses, have a great variety of styles and sizes of cable fittings attached thereto suitable for specific purposes. Heretofore, whenever a cable wore out, or became 50 defective for another reason, not only the cable

had to be removed and replaced, but the fittings had also to be discarded, since they could not readily be removed from the cable without being destroyed in the process. Since, as previously explained, there are so many different styles and sizes of these cable fittings in use that it is difficult at times to find a dealer in such supplies, who carries all styles in stock. By means of my invention, I have devised a device which will quickly and non-destructively remove a cable fitting from a defective cable, so that it may again be used on a new cable.

My device, as disclosed in the drawing, comprises a base or support 10 provided with a pair of upwardly extending ears, or bearing brackets 11 and 12, which are aligned and spaced from each other. A rocker arm 15 is rotatably mounted, intermediate its ends, on a shaft 16 which is rigidly mounted in the brackets 11 and 12. If desired, however, the rocker arm 15 may be rigidly mounted on the shaft 16 and the shaft 16 rotatably mounted in the brackets 11 and 12.

It is thus seen that the arm 15 is adapted to be rotated in either a clockwise or a counter-clockwise direction. The rotational movement 25 of the rocker arm 15 is limited in both directions by contact of the lower surfaces 17, 18 of the said arm, with the upper surface of the support 10. The said surfaces 17, 18 may be angularly inclined with respect to each other so that when 30 either the surface 17 or the surface 18 is in contact with the support surface it will be substantially parallel thereto.

Mounted on the support 10 is a pair of cooperating jaws 20 and 21. One of the jaws, such 35 as 21, is provided with a notch 22 at one end thereof, and the other of said jaws 20 is provided with an outwardly projecting portion 23 at one end thereof which is adapted to be received in the notch 22. The jaws 20 and 21 are 40 relatively movable toward and away from each other and are adapted to clamp a cable C of the character described between them. As shown in Figs. 1 to 3 of the drawing, the notch 22 of the jaw 21, which is held stationary, is adapted to 45 straddle the cable C, and the jaw 20 is moved toward the jaw 21 with sufficient force so that the projection 23 will press against the cable C to retain the same against vertical as well as lateral movement in the notch 22. Any suitable 50 means may be provided for moving the jaw 20 toward and away from its cooperating jaw 21, such as for example, slidably mounting the jaw 20, which may be trapezoidal in cross section in a correspondingly shaped guideway 25 provided 55

in the support 10. A screw threaded block 26 is fastened to the support 10 by such means as screws 27. Into the threaded portion of the block 26 is inserted a screw threaded shaft 28, one end 5 of which is adapted to abut against the movable jaw 20. A spring 30 is interposed between the jaws 20 and 21 which tends to normally urge the jaw 20 in a direction away from the jaw 21. It is thus seen that when the shaft 28 is rotated 10 in one direction the jaw 20 will be slidably moved toward the jaw 21 against the action of the spring 30, and when the shaft 28 is rotated in another direction, the jaw 20 will slidably move away from the jaw 21, due to the action of the spring 30. 15 To facilitate the rotation of the shaft 28 and in order to obtain sufficient pressure on the projection 23 against the cable C a handle 29 may be attached to the free end of the shaft 28. While 20 in the drawing I have shown a sliding bar type of handle, it is understood that any other suitable device may be employed, such as a fixed handle or a hand wheel, etc.

For non-destructively removing a cable fitting F from the cable C after the said cable has been 25 clamped between the jaws 20 and 21 in the manner described above, I have provided a construction comprising a member 31 which is rigidly mounted at one end of the arm 15 for movement therewith. The said member 31 may be substantially semi-tubular in shape, as shown in the drawing, or of any similar desired form and provided with a bottom wall 32. The said bottom wall 32 is provided with a notch 33 which is adapted to register with the notch 22 when the 30 bottom surface of the wall 32 contacts the top surface of the jaw 21 (see Figs. 1 and 3). The cable C is so positioned between the jaws 20 and 21 that the bottom shoulder 35 of the fitting F will contact the surface portion of the bottom 35 wall 32 surrounding the notch 33. It is thus seen that when the rocker arm 15 is caused to rotate in a counter-clockwise direction about the pivot 16, an upward force will be exerted on the shoulders 35 of the said fitting F, to ultimately 40 lift the fitting F off the end of the cable C, as illustrated by the dotted lines F' in Fig. 1 of the drawing. To facilitate the counterclockwise rotation of the arm 15 and to provide sufficient force for effectively removing the fitting F as 45 above described, I have provided the following mechanism:

Rigidly mounted on the support 10 is an upright rod 40 adapted to pass freely through an aperture 41 in the arm 15 and having the upper 50 end thereof threaded. A cap member 42 having a screw threaded aperture 43 therein is provided which is adapted to cooperate with the threaded portion of the rod 40. Interposed between the cap 42 and a washer 44, said washer being designed to contact the portion of the arm 15 adjacent the aperture 41, is a ball bearing device 55 of usual design in order to reduce the friction of the cap 42 on the washer 44. If desired, the arm 15 may be normally urged, by means of 60 a spring 46, to assume the position where the wall 32 will contact the jaw 21, as shown in Fig. 65 1 of the drawing.

It is clearly seen from the above-described construction that as the cap 42 rotates in one 70 direction, it will move downwardly to cause the washer 44 to rotate the arm 15 in a counter-clockwise direction against the action of the spring 46 and thus render the cable and fitting 75 disassembling operation effective. To facilitate the rotation of the cap 42 and in order to exert

a sufficient downward force to rotate the arm 15, a handle 50 may be provided which may be attached to the cap 42. While, in the drawing, I have shown a sliding bar type of handle, it is understood that any other suitable device may be 5 employed, such as a fixed handle, or a hand wheel, etc.

The notch 22 and cooperating projection 23, are so designed that the cable C when gripped between them will not be weakened to such an 10 extent as to cause breaking of the cable when the upward pulling force is applied to remove the fitting F. One way of effecting this result is to have the notch 22 of greater depth than the projection 23 and at the same time to bevel off 15 all the square corners of the notch 22 and projection 23.

It has also been found desirable to disassemble cable fittings and cables without first removing the casing 80 in which cables of the character 20 described are customarily designed to operate. The said casing 80 is usually made shorter than the cable, allowing for a certain amount of free longitudinal sliding. This distance is in the nature of $\frac{1}{4}$ " to $\frac{1}{2}$ ". Since it is desirable that the 25 casing be not destroyed in the act of removing a cable fitting it is seen that the cooperating jaws 26 and 21 as well as the bottom wall 32 of the above described pulling mechanism must not exceed in total thickness the above described 30 space between the casing 80 and the bottom 35 of the fitting F, as clearly shown in Figs. 1, 3 and 6 of the drawing.

Therefore, in order to meet all exigencies in 35 non-destructively removing a cable fitting from a cable, the bottom wall 32 of the member 31 and the jaws 20 and 21 may be preferably constructed to aggregate in thickness approximately $\frac{3}{8}$ " or less, but it is understood that this aggregate 40 thickness may be varied if desired, in accordance with the relative lengths of the cable and cable casing.

In order to add to the efficiency and usefulness of my device, I have provided, in addition to the above-described disassembling apparatus, means 45 for attaching a cable fitting to a cable.

My cable and fitting assembling apparatus 50 comprises a pair of opposed jaws 60 and 61. The jaw 60 may be rigidly mounted on the stationary support 10, while the cooperating jaw 61 may be 55 rigidly mounted on the rocker arm 15 for movement therewith. It is noted that the jaws are mounted on the opposite side of the pivot 16 from that of the disassembling apparatus, previously described, so that normally they will be disposed 60 in open position as shown in Fig. 1, due to the action of the spring 48. Each of the jaws 60 and 61 may comprise a semi-circular notched portion 62, having centrally located therein a projecting pin. In attaching the fitting F to the cable C, the 65 end of the said cable is first inserted in the aperture 63 in the fitting F and then the neck portion N of the fitting is positioned in the notch 62 of the jaw 60. The arm 15 carrying the cooperating jaw 61 is then caused to be moved toward the jaw 60 to clamp the fitting neck N between the jaws, by rotating the cap 42, in the same manner as hereinbefore described in connection with the 70 disassembling operation. When sufficient clamping force has been applied, the pins 64 will press 75 to form a crimp 64 in the neck N to fasten the fitting F to the cable C, after which operation the cap 42 may again be rotated to spread apart the jaws 60 and 61.

It has been found necessary at times to reduce 75

the diameter of the cable end in order that it may fit into the fitting aperture 63. I have therefore provided a pair of cooperating jaws 65 and 66 of any well-known suitable design for reducing the

5 diameter of a cable end with one of the jaws, such as 65, being mounted on the stationary support 10 and the cooperating jaw 66 being mounted on the arm 15. I have also provided a pair of cooperating jaws 67 and 68 for shearing or cutting

10 the cable to any desired length or for trimming the ends of the cable before attaching a fitting thereto, the jaws 67 being mounted on the support 10, while the jaw 68 is mounted on the arm 15. The pairs of jaws 65-66 and 67-68

15 may be suitably spaced with respect to the position of the pair of jaws 60-61. If desired, the three pairs of jaws just described may be adapted to be removed or replaced by pairs of jaws

20 designed to accommodate different sizes of fittings and cables. It is also understood that, if desired, pairs of jaws may be added to effect other similar operations found to be necessary in connection with cables and fittings of the character described.

25 My device may be adapted to be fastened to a bench B or to any other similar supporting means by employing suitably positioned bolts 70 for attaching the member 10 to said bench B.

It will thus be seen that there is provided a device in which the several objects of this invention are achieved, and which is well adapted to meet the conditions of practical use.

As various possible embodiments might be made of the above invention, and as various changes might be made in the embodiments set forth, it is to be understood that all matter herein contained, or shown in the accompanying drawing, is to be interpreted as illustrative and not in a limiting sense.

40 Having thus described my invention, I claim as new and desire to secure by Letters Patent:

1. A tool of the character described comprising a pair of slidably cooperating jaws for clamping a cable between them and non-clamping means adapted to act upon a fitting to forcibly and non-destructively remove the same from said cable.

2. A tool of the character described adapted to disassemble a cable and a fitting comprising a pair of pivotally interconnected members, cooperating jaws on one of the members for clamping a cable between them, and non-clamping means on the other of said members adapted to non-destructively remove said fitting from said cable.

3. A tool of the character described adapted to disassemble a cable and a fitting comprising a pair of pivotally interconnected members, means on one of said members for holding a cable and non-holding means on the other of said members adapted to non-destructively remove said fitting from said cable.

4. A tool for disassembling one member from another member comprising means for gripping one of said members to hold the same against movement, a support for said gripping means, non-gripping means adapted to act upon the other of said members to separate the first from the second of said members, a support for said non-gripping means, and means for interconnecting said supports for relative pivotal movement.

5. A tool of the character described adapted to disassemble a cable and a fitting comprising a pair of pivotally interconnected members, cooperating jaws on one of the members for clamp-

ing a cable between them, and means on the other of said members for non-destructively removing a fitting from said cable, said last-named means comprising a member having a bottom wall provided with a notch adapted to straddle 5 said cable.

6. A tool of the character described adapted to disassemble a cable and a fitting comprising a pair of pivotally interconnected members, cooperating jaws on one of the members for clamping 10 a cable between them, and means on the other of said members for non-destructively removing a fitting from said cable, said last-named means comprising a member having a bottom wall provided with a notch adapted to straddle said cable, 15 said bottom wall being adapted to overlie the said jaws.

7. A tool of the character described adapted to disassemble a cable and a fitting comprising a pair of pivotally interconnected members, cooperating jaws on one of the members for clamping 20 a cable between them, and means on the other of said members for non-destructively removing a fitting from said cable, said last-named means comprising a member having a bottom 25 wall provided with a notch adapted to straddle said cable, said bottom wall being adapted to overlie the said jaws, whereby said notch will register with the space between said jaws occupied by the said cable when the said jaws are in 30 cable clamping position.

8. A tool of the character described adapted to disassemble a cable and a fitting comprising a pair of pivotally interconnected members, cooperating jaws on one of the members for clamping 35 a cable between them, and means on the other of said members for non-destructively removing a fitting from said cable, said last-named means comprising a member having a bottom wall provided with a notch adapted to straddle 40 said cable, said bottom wall being adapted to overlie the said jaws, whereby said notch will register with the space between said jaws occupied by the said cable when the said jaws are in cable clamping position, a portion of said bottom wall surrounding the said notch being adapted to contact the portion of the end of said fitting surrounding the cable.

9. A tool of the character described adapted to disassemble a cable from a fitting comprising 50 a pair of pivotally interconnected members, cooperating jaws on one of said members for clamping a cable between them, means for forcing said cable and said fitting apart to disassemble them, and means for rendering said forcing means effective.

10. A tool of the character described adapted to disassemble a cable from a fitting comprising a pair of pivotally interconnected members, cooperating jaws on one of said members for clamping 60 a cable between them, means for forcing said cable and said fitting apart to disassemble them, and means for rendering said forcing means effective, said last-named means including means for relatively moving said pivotally interconnected members.

11. A tool of the character described adapted to disassemble a cable from a fitting comprising a pair of pivotally interconnected members, cooperating jaws on one of said members for clamping a cable between them, means for forcing said cable and said fitting apart to disassemble them, and means for rendering said forcing means effective, said last-named means including means for rela- 75

tively moving said pivotally interconnected members away from each other.

12. A tool of the character described, adapted to disassemble a cable in a casing from a fitting comprising a pair of pivotally interconnected members, cooperating jaws on one of the members for clamping a cable between them and means on the other of said members for non-destructively removing a fitting from said cable, said last-
10 named means comprising a member having a bottom wall provided with a notch adapted to straddle said cable, the thickness of said bottom wall and the thickness of said cooperating jaws aggregating less than one-half inch whereby said bottom wall and said jaws may be interposed between the inner end of the said fitting and one end of the said casing.

13. In a tool of the character described, in combination, a pair of members pivotally connected intermediate their ends, means for non-destructively removing a fitting from a cable, and means for attaching a fitting to a cable, said fitting removing means being mounted on said members on one side of said pivot and said fitting attach-

ing means being mounted on said members on the other side of said pivot from said fitting removing means.

14. In a tool of the character described, in combination, a pair of members pivotally connected intermediate their ends, means for non-destructively removing a fitting from a cable, and means for cutting a cable, said fitting removing means being mounted on said members on one side of the said pivot and said cable cutting means being mounted on said members on the other side of the said pivot from said fitting removing means.

15. In a tool of the character described, in combination, a pair of members pivotally connected intermediate their ends, means for non-destructively removing a fitting from a cable, and means for reducing the diameter of a cable end, said fitting removing means being mounted on said members on one side of the said pivot and said diameter reducing means being mounted on said members on the other side of the said pivot from said fitting removing means.

ISIDORE FINKEL.
